MULTIHULL BOAT

Herman Sydney Heyman, 2737 Devonshire Place,
Washington, D.C. 20008

Filed Jan. 18, 1971, Ser. No. 107,606

Term of patent 14 years

Int. Cl. D12—06

U.S. Cl. D71—1

FIG. 1

FIG. 2

FIG. 3

FIG. 4

FIG. 5

FIG. 1 is a rear perspective view of a multihull boat showing my new design;

FIG. 2 is a rear view thereof;

FIG. 3 is a rear view of a modified form thereof wherein the only difference resides in the support structure;

FIG. 4 is a bottom view thereof;

FIG. 5 is a front view thereof.

I claim:

The ornamental design of a multihull boat, substantially as shown and described.
